AIR CONDITIONING SYSTEM

William L. McGrath, Philadelphia, Pa., assignor
to Minneapolis-Honeywell Regulator Com-
pany, Minneapolis, Minn., a corporation of
Delaware

Application November 15, 1941, Serial No. 419,302

16 Claims. (Cl. 257—3)

This invention relates to air conditioning systems and controls therefor.

The object of the invention is to provide a simple, inexpensive, but effective arrangement for providing for both temperature and humidity control using a minimum of controls and control mechanism.

More specifically, the object of the invention is to provide means for shifting from modulating to substantially on and off control in a system wherein cooling is normally modulated in response to temperature, when there is a need for dehumidification of the air being treated. Thus when the control is shifted to on and off control, the temperature continues to be controlled, but when there is cooling it is effected at a lower temperature, the cooling means operating at its maximum rate so that there will be more dehumidification and the humidity will be brought back to the desired value.

Another object is to control the cooling in response to load demands as measured by outdoor temperature when the control has been shifted to on and off.

Many additional objects and advantages of my invention will become apparent from the following detailed description and annexed drawing.

Referring to the drawing there is shown a heating and cooling system of the type wherein hot water or cold water is circulated to spaces wherein the air is to be kept at predetermined conditions of temperature and humidity. The water is circulated to the spaces by means of an electric motor driven circulator indicated on the drawing by the numeral 10. The water may be circulated through radiators in the space or spaces being served or it may be circulated to unit air-conditioners or other similar devices in the spaces. The water is returned from the heat exchange devices in the various spaces through a pipe 11. The water returning through the pipe 11 may be passed through a water heater designated by the numeral 12, by means of a pipe 13 or it may be passed through a water cooler 14 by means of pipe 15. The water heater 12 and the water cooler 14 may each be of any suitable type of heat exchanger such as the shell and tube type, for example. Steam is circulated through the water heater 12 for heating the water going therethrough, the steam being admitted through a pipe 16 and the condensate being withdrawn through pipe 17. Disposed in the pipe 16 is a steam control valve 18 of the thermostatic type, the valve being controlled by a thermostatic mechanism 19 including a thermal

bulb 20 disposed in heat exchange relationship with a portion of the water heater 12, the bulb being connected to the thermostatic mechanism 19 by a capillary tube 21. The valve 18 and the thermostatic mechanism 19 are preferably of the electric proportioning type or they may be of any other suitable type, for example, they might be of a self contained type. The function of the thermostatic mechanism and steam valve is to maintain a predetermined temperature in the heat exchanger, that is, in the water heater. Thus when heating is required in the spaces water at a suitably high temperature will be available for maintaining the temperature.

15 As pointed out, the water cooler 14 may be a heat exchanger of substantially the same type as the water heater 12 and any suitable type of cooling apparatus may be used for cooling the water in the cooler 14.

20 The water which passes through the water heater and the water cooler is discharged into a riser pipe designated by the numeral 23. The riser connects to the inlet side of the circulator 10 and the circulator then circulates the water 25 to the heat exchange devices in the spaces as already pointed out.

Connected between the pipe 11 and the riser 23 is a by-pass pipe 24 which serves to by-pass water between the pipes 11 and 23 without its passing 30 through either the water heater or the water cooler. At the juncture of pipe 24 with riser 23 is disposed a three-way valve 25 which valve is of a type well known in the art and which is arranged to control the proportions of water going 35 through the water cooler 14 and the by-pass pipe 24. This type of three-way valve control is well known in the art and need not be described in further detail. The valve member of the three-way valve is positioned by means of a rack and pinion designated by the numerals 26 and 27. The pinion 27 is driven by a reversible electric motor designated by the numeral 28, the motor comprising windings 29 and 30, the two windings being associated with armatures 31 and 32 respectively.

40 When one winding is energized the motor operates in one direction and when the other winding is energized the motor operates in the other direction. The motor drives the pinion 27 through a gear train designated diagrammatically by the numeral 33. On the shaft of one of the gears of the gear train, preferably the same shaft on which is mounted the pinion 27, is a rotatable switch actuating finger 34. This finger cooperates with a pair of limit switches designated 35 and 36. Each of the limit switches has a blade,

the end of which is extended slightly so as to be engageable by the finger 34 so that when the electric motor drives the three-way valve 25 to either of its limit positions that is, its wide open or fully closed positions, one of the limit switches will be opened by cooperation of the finger 34 with the extended blade of the respective switch. As will presently be pointed out the electric motor is deenergized when its windings are deenergized by opening of the limit switches.

At the juncture of the pipe which carries water away from the water heater 12 with the riser 23 is a second three-way valve 40 which is of exactly the same construction as the three-way valve 25, this valve serving to proportion the relative quantities of water which pass through the water heater 12 and through the by-pass 24. It may be mentioned at this time that when heating is required in the spaces the three-way valve 25 will be in a position to prevent any water from going through the water cooler 14. In this position of three-way valve 25 water may freely pass through by-pass 24 to the riser 23. On the other hand when cooling is required in the spaces the three-way valve 40 will be in a position to prevent any water from going through the water heater 12 and in this position of three-way valve 40 water may freely pass upwardly in the riser 23 through the three-way valve 40. The three way valve 40 is driven by a reversible electric motor 28a which is of exactly the same type as the motor 28 so that it need not be described in detail. The motor 28a is controlled by a control arrangement corresponding to that which controls the motor 28 and these controls will be described hereinafter.

The controls for motor 28 of three-way valve 25 are of the electrical proportioning type. The controls for motor 28 include a potentiometer type controller 41 having a slide wire resistance 42 cooperating with which is a pivoted slider 43. The slider 43 is operated by an expandable and contractible bellows 44, the movable end of the bellows carrying a stem which abuts against the slider 43 at a point spaced from the pivot of the slider. The slider is normally urged in to engagement with the operating stem of the bellows by a coil spring 45. The interior of the bellows is connected to a thermal bulb containing a volatile liquid the thermal bulb being designated by the numeral 46, and this bulb being disposed in intimate thermal contact with the riser 23 just beyond the three-way valve 25. The volatile liquid in the thermal bulb and bellows expands, that is it vaporizes and develops a pressure depending upon the temperature in the riser 23 and upon a rise in pressure in the bellows it expands, moving the slider 43 to the right along resistance 42, and upon a drop in temperature in the riser 23 the bellows 44 contracts moving the slider 43 to the left along the resistance 42. Numeral 49 designates a balanced relay comprising windings 50 and 51 associated with an armature 52 which is normally in an intermediate balanced position when the windings 50 and 51 are equally energized. The armature 52 is connected to a switch blade 53 which cooperates with fixed electrical contacts 54 and 55. When the energization of winding 50 preponderates over that of winding 51 the armature 52 is moved to the left bringing blade 53 into engagement with contact 54 and when the energization of winding 51 preponderates over that of winding 50 the armature 52 is moved to the right moving switch blade

53 into engagement with contact 55. When the relay is in a normally balanced position the blade 53 is in a position intermediate contacts 54 and 55. The left end of resistance 42 is connected to the left end of winding 50 by wires 56, 57 and protective resistance 58. The right end of resistance 42 is connected to the right end of winding 51 by wires 59, 60 and protective resistance 61. The slider 43 is connected to the juncture of the windings 50 and 51 as will be pointed out.

Power for operation of balanced relay 49 is supplied by a transformer 62, having a primary winding 63. Connected to line conductors 120 and 121 by wires 122 and 123. The transformer has a secondary winding 39, the left end of which is connected to winding 50 by wire 37 and the right end of which is connected to winding 51 by wire 38.

Numeral 65 designates a second potentiometer type controller similar to the controller 41. The controller 65 comprises a slide wire resistance 66 cooperating with which is a pivoted slider 67 which is actuated by an expandable and contractible bellows 68, the movable end of which carries a stem which normally abuts the slider 67 at a point spaced from the pivot point of the slider. The slider is normally urged into engagement with the operating stem of the bellows by a coil spring 69. The interior of the bellows is connected to a thermal bulb 70 by a capillary tube 71. The thermal bulb 70 of controller 65 is disposed outdoors so as to be responsive to outdoor temperature. Thus the volatile liquid in bulb 70 vaporizes and develops a pressure in accordance with outdoor temperature. When the outdoor temperature rises the pressure in the bulb and bellows increases thus moving slider 67 in a clockwise direction, that is upwardly on resistance 66. When the outdoor temperature falls, conversely there is a drop in pressure in bellows 68 and slider 67 is moved downwardly along resistance 66. The upper end of resistance 66 is connected to the right end of winding 51 by wires 72, 60 and protective resistance 61. The lower end of resistance 66 is connected to the left end of winding 50 by wire 73, wire 57 and protective resistance 58. The slider 67 like the slider 43 is connected to the juncture of windings 50 and 51 as will be pointed out.

The purpose of protective resistances 58 and 61 is to prevent the secondary of transformer 62 from ever being shorted as will appear.

Numeral 75 designates a humidity responsive controller which controls a relay which cooperates with the potentiometer controllers 41 and 65. The humidity controller comprises a humidity responsive element 76 which is of the type comprised of a number of strands of human hair which tend to lengthen upon an increase in humidity and which shorten upon a decrease in humidity. The humidity responsive element is connected to a pivoted switch carrying lever 77 which carries a mercury switch 78, the lever normally being biased in a clockwise direction by a coil spring 79. The controller 75 controls a relay 80 having a winding 81 and an armature associated therewith which is connected to a movable switch blade 82 which is moved to the right out of engagement with a fixed electrical contact 83 when the winding 81 is energized. The armature of relay 80 is connected to a second movable switch blade 84 which normally engages a fixed electrical contact 85 when the relay is deener-

gized and which moves to the right into engagement with a fixed electrical contact 86 when the relay is energized.

The slider 43 of controller 41 is connected to the juncture of windings 50 and 51 by a wire 87, contact 85, blade 84, and wire 89 this connection of course being complete when the relay 80 is de-energized. The slider 67 of controller 65 is connected to the juncture of windings 50 and 51 by wire 90, wire 87, contact 85, blade 84, and wire 89. From the foregoing circuits it can be seen that when the relay 80 is energized the sliders 67 and 43 are disconnected from the windings of the balanced relay 49 which relieves the controllers 41 and 65 of control. When the relay 80 is energized the winding 51 of the balanced relay 49 is substantially shunted by means of the following circuit: From the right end of winding 51 through protective resistance 61, wire 60, wire 92, contact 86, blade 84, and wire 89 to the juncture of windings 50 and 51. When winding 51 is thus substantially shunted the energization of winding 50 preponderates and blade 53 is moved into engagement with contact 54. As will be explained in the description of operation herein-after this will cause the motor 28 to operate to move the three-way valve 25 to a position wherein no water passes through the by-pass 24 and all of the water being circulated by the circulator 10 passes through the water cooler 14.

The controls for the motor 28a of three-way valve 40 correspond to the controls for the motor 28 of three-way valve 25. The controller for motor 28a which is responsive to the riser temperature is designated 41a and the controller associated with motor 28a which is responsive to outdoor temperature is designated 65a. In as much as these controls are exactly like the controls which they correspond to and which have already been described in detail they need not be further described. However, it is to be pointed out that the controls for motor 28a are not interlocked with the relay 80 as are the controls associated with motor 28. That is, the sliders of the potentiometer controllers included in the controllers 41a and 65a are not connected to the balanced relay of this control arrangement through contact 85 of the relay 80. These particular controls in themselves are of course well known in the art.

The controls for the system include another controller responsive to outdoor conditions, this controller being designated by the numeral 95. The controller 95 is of a type arranged to respond to outdoor temperature and other weather conditions such as solar radiation, wind conditions, etc. The controller 95 comprises an enclosure 96 which is formed of a material having a relatively great thermal mass. Within the upper part of this enclosure 96 is a bimetal element 97 which cooperates with a fixed electrical contact 98 and the bimetal element carries a switch blade 99 which cooperates with a fixed electrical contact 100. In the lower part of the controller 95 there is an open space within which is an electrical heater 101 which serves to heat the controller and as will be described its function is to maintain the body of the controller at a temperature somewhat higher than the ambient temperature, that is, somewhat higher than outdoor temperature. Thus heat will be dissipated from the controller at a rate dependent not only upon the outdoor temperature but also upon the amount of solar radiation, the wind velocity and so forth. The controller 95 is in itself a device already

known in the art and which is normally employed in a heating system, for example, so as to control the operation of a heating plant so as to deliver heat to spaces being heated dependently upon heating requirements as measured by outdoor weather conditions including the outdoor temperature, the amount of solar radiation, and wind velocity and so on as pointed out above. In carrying out this function the heater 101 of the controller bears a definite relationship to the heating capacity of the plant which is controlled by the controller. Thus, there is a definite relationship between the heating of the controller 95 and the heat supplied to the building or the structure being served. It follows that the controller 95 will maintain itself at a certain temperature and the heating plant will be operated to maintain a given predetermined temperature in the spaces being heated. However, in my particular arrangement the controller 95 is used to control the cooling rather than the heating and this will be described presently. The controller 95 controls a relay 103 comprising a winding 104, having an armature associated therewith connected to movable switch blades 105 and 106. The blade 106 normally engages a fixed electrical contact 107 when the relay 103 is deenergized and when the relay is energized the blades 105 and 106 are moved to the left into engagement with fixed electrical contacts 108 and 109 respectively. Power for operation of the relay 103 is supplied by a step-down transformer 110 having a primary winding 111 and a secondary winding 112, the primary winding having the greater number of turns. Power is supplied to the primary winding through wires 113, and 114 which may be connected to any suitable source of external power not shown. The operation of the controller 95 in connection with the relay 103 will be described in more detail hereinafter.

Referring now to the operation of the system as a whole, the operation will first be described when cooling of the spaces is required as in the summertime. During the summertime when cooling is required it is to be understood that the source of steam supply is inactive so that no steam is being supplied to the water heater 12. With the parts in the position shown on the drawing the humidity has not risen to too high a value, the relay 80 is deenergized and the circulator 10 is in operation. Its circuit is as follows: from line 145 to wire 149, contact 83, blade 82, wire 144, wire 150, the motor of circulator 10, and wire 151 back to line conductor 148. The three-way valve 40 is in a position to prevent any water from circulating through the water heater 12 and to permit water to rise freely through the riser 23. Water is being cooled in the water cooler 14 and the flow of water through the system is under control of the three-way valve 25 which is in turn being controlled by the controllers 41 and 65. Assuming that the outdoor temperature is at a given value the three-way valve 25 will be positioned in response to the controller 41 to maintain the water going through the riser 23 to the spaces at a predetermined temperature. This predetermined temperature will be one bearing a fixed relationship to the outdoor temperature as will presently appear. In other words, the function of the controller 65 is to adjust the control point of controller 41 so that the controller 41 will maintain a temperature in the riser at a value determined by outdoor temperature. Assuming now that the outdoor temperature is such that the control

point of controller 41 has been adjusted so that it will maintain a riser temperature of 35°. If now the temperature in the riser 23 rises above this value the bellows 44 will expand moving slider 43 to the right along resistance 42. This will partly shunt out the winding 51 and consequently the energization of winding 50 will preponderate and will unbalance the relay moving the blade 53 to the left into engagement with contact 54. Winding 29 of the motor 28 will now be energized through the following circuit: from line conductor 120 through wire 126, blade 53, contact 54, wire 127, limit switch 35, wire 128, winding 29, wire 129, back to line conductor 121. Motor 28 will now operate in a direction to position the three-way valve 25 to cause more water to pass through the cooler 14 and less through the by-pass 24 so that the temperature in the riser 23 will tend to fall back to the desired value. When the temperature in the riser has fallen back to the desired value of 35° for example, the controller 41 will reassume its original position rebalancing the relay 49 and thus moving blade 53 away from contact 54 and again deenergizing the motor 28 leaving the valve 25 in its new position. On the other hand, if the temperature in the riser falls below the desired value bellows 44 will contract moving slider 43 to the left along resistance 42. This will partly shunt out the winding 50 and so the winding 51 will preponderate moving the blade 53 to the right into engagement with contact 55. This will complete a circuit energizing the winding 30 of the motor 28 as follows: from line conductor 120 through wire 126, blade 53, contact 55, wire 131, limit switch 36, wire 132, winding 30, and wire 129 back to line conductor 121. Motor 28 will now operate in a direction to move the three-way valve to a position to cause less water to go through the cooler 14 and more to go through the by-pass 24. Thus the temperature in the riser 23 will rise again to its desired value and the controller 41 will reassume its original position rebalancing the relay 49 and moving switch blade 53 to its intermediate position and interrupting the circuit of the motor 28. Thus the motor will stop leaving the three-way valve 25 in its adjusted position.

When there is a rise in outdoor temperature it will of course be necessary to circulate colder water to the spaces. Thus when the outdoor temperature rises, the slider 67 will be moved upwardly along resistance 66 and the result of this will be to partly shunt out the winding 51 in the same manner as it is partly shunted out when the slider 43 moves to the right. The relay 49 will again be unbalanced in a direction to bring the switch blade 53 into engagement with contact 54 and the three-way valve 25 will be operated in opening direction, that is, in a direction to cause more water to go through the water cooler 14 and less through the by-pass 24. As the three-way valve is now operated in this manner the riser temperature will of course tend to fall. Thus the bellows 44 will contract moving slider 43 to the left which will have an effect on the relay 49 just the opposite of course to the effect of the movement of the slider 67 upwardly along resistance 66. Thus the controller 41 acts as a rebalancing controller and whenever the controller 65 assumes a new position to cause water to flow through the riser 23 at a different temperature the controller 41 will assume a new rebalancing position at which the

motor 28 will stop leaving the valve 25 in its adjusted position. The controller 65 has the effect of a compensating controller. Whenever the outdoor temperature is stable the controller 41 will of course control in the manner described to maintain the temperature in the riser at a predetermined value which as pointed out is of course determined by the controller 65. The controller 41 preferably of course has a relatively narrow operating differential, that is, it need move the slider 43 over only a small part of resistance 42 to cause a relatively large movement of the valve 25. The function of the controller 65 is therefore, to adjust the control point of the controller 41 to any part of the resistance 42. Thus the controller 65 may act to cause the controller 41 to maintain the riser temperature at any value of from 0° to 70° for example. In practice the controller 65 will be adjusted to be effective within a range of from 60 to 100° F. for example. As the outdoor temperature rises the controller 41 will be so affected as to maintain lower and lower riser temperatures and as the outdoor temperature falls the controller 41 will be so affected as to maintain higher and higher riser temperatures.

During summer operation when the humidity in the spaces rises to a predetermined relatively high value the humidity responsive controller 75 will respond to close its mercury switch 78 and energize the relay 80. When the mercury switch 78 closes, the relay is energized through the following circuit: from wire 132, to wire mercury switch 78, wire 133, winding 81, back to wire 134, the wires 132 and 134 being connected to any suitable source of power not shown. When the relay 80 is energized switch blades 82 and 84 are moved to the right blade 84 moving into engagement with fixed contact 86 and blade 82 disengaging from contact 83. Disengagement of blade 82 from contact 83 places the circulator 10 under control of the controller 95 as will presently be described. Disengagement of blade 84 from contact 85 disconnects the controllers 41 and 65 from the balancing relay so that they have no further control. Engagement of blade 84 with contact 86 substantially shunts the winding 51 of the balanced relay so that the winding 50 preponderates causing blade 53 to engage contact 54. The motor 28 now operates in a direction to move valve 25 to a position wherein all of the water passes through the cooler 14 and none of it through the by-pass 24. The motor 28 will under these circumstances operate to its limiting position wherein limit switch 35 is opened and the valve 25 is in an extreme position wherein all of the water goes through the water cooler as pointed out.

The circulator 10 is now controlled by the relay 103 which is responsive to the controller 95. When the relay 103 is deenergized the heater 101 is not energized and the temperature of the controller 95 falls due to dissipation of heat therefrom by reason of the outdoor temperature being lower than the temperature of the controller and due to heat being carried away as a result of wind and so on. When the temperature of the controller falls to a predetermined value the bimetal element 97 will be brought into engagement with contact 98 and blade 99 will engage contact 100. The arrangement is such that the blade 99 engages contact 100 before the bimetal element engages contact 98 that is, the contact 98 is engaged by a bimetal element 97 at a slightly lower temperature than the temper-

ature at which blade 99 engages contact 100. When both the switch contacts are engaged a circuit is completed for the winding 104 as follows: from secondary 112 of transformer 110 through wire 135, winding 104, wire 136, contact 98, bimetal element 97, blade 99, contact 100, and wire 137 back to secondary 112. Energization of winding 104 causes blades 105 and 106 to move to the left into engagement with contact 108 and 109 respectively. Engagement of blade 105 with contact 108 completes a maintaining circuit for the relay winding 104 as follows: from secondary 112 through wire 135, winding 104, wire 138, blade 105, contact 108, wire 139, bimetal element 97, blade 99, contact 100, and wire 137 back to secondary 112. Thus, by reason of this maintaining circuit the relay will not be deenergized until the temperature of the controller 95 has risen to a high enough value to cause blade 99 to disengage from contact 100. Engagement of blade 106 with contact 109 completes a circuit for the heater 101 as follows: from wire 145, to blade 106, contact 109, wire 146, heater 101 and wire 147 back to wire 148, the wires 145 and 148 being connected to any suitable source of power not shown. Whenever blade 106 is out of engagement with contact 107 the circuit for the motor of the circulator 10 is interrupted and the circulator does not act to forcibly circulate water to the spaces being served. When heater 101 is energized the temperature of controller 95 will of course tend to rise, the heat being supplied at a greater rate than it is dissipated and bimetal element 97 will move to the right disengaging from contact 98 and eventually causing blade 99 to disengage from contact 100 and deenergizing the relay. When relay 103 is deenergized a circuit is completed for the motor of circulator 10. This circuit is as follows: from wire 145 to blade 106, contact 107, wire 143, wire 150, the motor of circulator 10, wire 151, back to wire 148. The circulator 10 will thus operate to forcibly circulate cold water through the spaces being served as long as the relay 103 is deenergized. The water being circulated will be at the lowest possible temperature because the valve 25 is in a position to circulate all of the water through the water cooler. Thus, inasmuch as this water is at its lowest possible temperature, maximum dehumidification will be effected in the spaces being served and the humidity will tend to fall back to its desired value. Operating in this manner the controller 95 will of course cycle on and off in the manner described, the circulator being turned on when the controller 95 has the relay 103 deenergized and the circulator being stopped when the controller 95 has the relay 103 energized. In other words, cooling is effected at a maximum rate in the spaces being served when the heater 101 is off, allowing the controller 95 to cool. On the other hand, when the heater 101 is in operation the circulator 10 is stopped and the temperature of the zone being served rises by reason of the outdoor temperature being relatively high. As is to be understood when the humidity is high and the relay 80 is energized and the circulator 10 is turned off and on the control is primarily in response to the outdoor temperature and other weather conditions affecting the controller 95. That is, when the humidity rises high enough to cause closure of the mercury switch 78 the control is shifted from modulating control of the three-way valve 25 to substantially on and off control by means of the circulator 10.

When the humidity drops back to the desired value the relay 80 is deenergized and the controllers 41 and 65 resume control of the three-way valve 25 and it is again positioned in response to riser temperature and outdoor temperature.

When the outdoor temperature falls down to a range wherein heating of the spaces rather than cooling is desired the three-way valve 25 will be in a position wherein all of the water passes through the by-pass 24 and none of it through the cooler 14. The outdoor controller 65 may be adjusted so that the three-way valve 25 assumes this position when the outdoor temperature reaches 70° for example. As the outdoor temperature continues to fall the controller 65a in response to the bulb 70a will operate motor 28a so as to cause three-way valve 40 to move to a position wherein part of the water goes through the water heater 12. The three-way valve 40 will now be positioned in response to the controllers 41a and 65a in the same manner as the three-way valve 25 is controlled by the controllers 41 and 65 when cooling is required. In other words, the controller 41a will maintain a predetermined riser temperature depending upon the outdoor temperature. The thermostatic mechanism controlling the steam valve 18 will maintain the temperature of the water going through the water heater 12 at a value suitable for heating in the spaces being served.

From the foregoing it should be apparent to those skilled in the art that I have provided a very efficient and inexpensive system whereby both temperature and humidity conditions may be maintained at desired values with a minimum of controls and without resorting to a complex and involved arrangement. By merely shifting the control from modulating to substantially on and off by means of the circulator, the humidity can be kept at a desired value even though the temperature continues to be controlled in response to controls which measure the temperature regulating requirements.

The embodiment of my invention disclosed herein is representative of a preferred form and since many variations and modifications may occur to those skilled in the art the disclosure is to be interpreted in an illustrative rather than limiting sense. The invention is to be limited only in accordance with the claims appended hereto.

I claim as my invention:

1. In a system of the class described, in combination, valve means for controlling a flow of medium for regulating the temperature of a space, temperature responsive means of the type arranged to modulatingly adjust the valve means, humidity responsive means arranged to cause the valve means to assume an extreme position when the humidity reaches a predetermined value, and control means whereby the flow of medium is at a maximum or minimum after the humidity has reached said predetermined value.

2. In apparatus of the character described, in combination, a conditioning system including a valve for controlling a flow of fluid medium for conditioning air, means responsive to a temperature representative of conditioning requirements arranged to modulatingly adjust the valve, means responsive to humidity of conditioned air for causing the valve to assume a flow position wherein the temperature of the fluid medium is at a minimum value, and means responsive to temperature regulating requirements for adjusting the flow of medium between a maximum and

a minimum rate after the humidity has caused the valve to assume said position.

3. In apparatus of the character described, in combination, a conditioning system including a valve for controlling a flow of fluid medium for conditioning air, means responsive to a temperature representative of conditioning requirements arranged to modulatingly adjust the valve, means responsive to humidity of conditioned air for causing the valve to assume a flow position wherein the temperature of the fluid medium is at a minimum value, and means responsive to temperature regulating requirements for adjusting the flow of medium between a maximum and a minimum rate after the humidity has caused the valve to assume a maximum flow position, said means responsive to temperature regulating requirements including means responsive to outdoor temperature.

4. In apparatus of the character described, in combination, cooling means and means for circulating fluid medium from said cooling means to a space to be cooled, a by-pass for said fluid medium around said cooling means, three way valve means controlling the proportions of said fluid medium flowing through said cooling means and by-pass, and means responsive to temperature regulating requirements controlling the valve means so as to adjust the temperature of medium flowing to the space so as to maintain a desired temperature therein, humidity responsive means for adjusting the valve means to cause medium at a minimum temperature to flow to the space and means whereby medium at said minimum temperature flows to the space alternately at relatively high or relatively low rates.

5. In apparatus of the character described, in combination, cooling means and means for circulating fluid medium from said cooling means to a space to be cooled, a by-pass for said fluid medium around said cooling means, three way valve means controlling the proportions of said fluid medium flowing through said cooling means and by-pass, and means responsive to temperature regulating requirements controlling the valve means so as to adjust the temperature of medium flowing to the space so as to maintain a desired temperature therein, humidity responsive means for adjusting the valve means to cause medium at a minimum temperature to flow to the space, means whereby medium at said minimum temperature flows to the space alternately at relatively high or relatively low rates, and means dependent upon the magnitude of the cooling load for selecting the rate of flow of said medium.

6. In apparatus of the character described, in combination, cooling means and means for circulating fluid medium from said cooling means to a space to be cooled, a by-pass for said fluid medium around said cooling means, three way valve means controlling the proportions of said fluid medium flowing through said cooling means and by-pass, and means responsive to temperature regulating requirements controlling the valve means so as to adjust the temperature of medium flowing to the space so as to maintain a desired temperature therein, humidity responsive means for adjusting the valve means to cause medium at a minimum temperature to flow to the spaces, a circulator for circulating fluid medium to the spaces, and means responsive to a condition representative of cooling load requirements for turning the circulator on and off when

the valve means have been adjusted by the humidity responsive means.

7. In apparatus of the character described, in combination, cooling means and means for circulating fluid medium from said cooling means to a space to be cooled, a by-pass for said fluid medium around said cooling means, three way valve means controlling the proportions of said fluid medium flowing through said cooling means and by-pass, and means responsive to temperature of medium and outdoor temperature controlling the valve means so as to adjust the temperature of medium going to the space to maintain a desired temperature therein, humidity responsive means for adjusting the valve means to cause medium at minimum temperature to flow to the spaces, and means for stopping and starting the flow of medium.

8. In apparatus of the character described, in combination, cooling means and means for circulating fluid medium from said cooling means to a space to be cooled, a by-pass for said fluid medium around said cooling means, three way valve means controlling the proportions of said fluid medium flowing through said cooling means and by-pass, and means responsive to temperature of medium and outdoor temperature controlling the valve means so as to adjust the temperature of medium going to the space to maintain a desired temperature therein, humidity responsive means for adjusting the valve means to cause medium at minimum temperature to flow to the spaces, said last means including means responsive to temperature maintaining requirements of the space.

9. In apparatus of the character described, in combination, means for heating a fluid medium, means for cooling said medium, means for circulating said medium to a space, means comprising two three-way valves whereby the medium can be made to flow through either the cooling means or the heating means and in by-pass relation with the cooling and heating means, the valves controlling the proportion of medium by-passed, means responsive to temperature changing load requirements controlling said valves dependently on whether or not heating or cooling is necessary, means comprising a humidity responsive device for causing all the medium to go through the cooling means, and means for causing the flow of medium to be substantially stopped and started in response to temperature regulating requirements when all the medium goes through the cooling means.

10. A system of the character described comprising in combination, temperature changing apparatus for cooling the air in a space to be conditioned, temperature responsive means for modulatingly varying the effectiveness of said apparatus for maintaining said air at the desired temperature, and means including humidity responsive means for alternately rendering said apparatus ineffective and effective at substantially maximum capacity for removing moisture from the air when the humidity increases above a predetermined value.

11. A system of the character described comprising in combination, temperature changing apparatus for cooling the air in a space to be conditioned, temperature responsive means for modulatingly varying the effectiveness of said apparatus for maintaining said air at the desired temperature, means including humidity responsive means for alternately rendering said apparatus ineffective and effective at substantially

maximum capacity for removing moisture from the air when the humidity increases above a pre-determined value, and means for varying the relative lengths of said alternate ineffective and effective periods in accordance with the cooling load on said system.

12. The method of controlling cooling apparatus for conditioning the air in a space, which comprises the steps of, modulating the effectiveness of said apparatus in accordance with the demand for cooling as long as the relative humidity of the air in said space is proper, and rendering said apparatus alternately ineffective and effective at substantially maximum capacity when the relative humidity of the air in said space becomes too high.

13. The method of controlling cooling apparatus for conditioning the air in a space, which comprises the steps of, modulating the effectiveness of said apparatus in accordance with the demand for cooling as long as the relative humidity of the air in said space is proper, and rendering said apparatus alternately ineffective and effective at substantially maximum capacity when the relative humidity of the air in said space becomes too high, and varying the relative lengths of said alternate ineffective and effective periods in accordance with the cooling load.

14. A system of the character described comprising in combination, cooling apparatus, means for circulating a fluid medium through said cooling apparatus and to a heat exchanger for conditioning the air in a space, means for varying the effectiveness of said cooling apparatus for regulating the temperature of said air, and means including a humidity responsive device for ren-

dering said cooling apparatus effective at substantially its maximum capacity and for causing said fluid medium to flow intermittently to said heat exchanger.

15. A system of the character described comprising in combination, cooling apparatus, means for circulating a fluid medium through said cooling apparatus and to a heat exchanger for conditioning the air in a space, means for varying the effectiveness of said cooling apparatus for regulating the temperature of said air, means including a humidity responsive device for rendering said cooling apparatus effective at substantially its maximum capacity and means for causing said fluid medium to have alternate flow periods and non-flow periods wherein the relative lengths of said periods are varied in accordance with the cooling load.

16. A system of the character described comprising in combination, cooling means, means for circulating fluid medium from said cooling means to a heat exchanger for conditioning air for a space, valve means controlling the flow of fluid medium through said cooling means, means responsive to temperature requirements controlling the valve means so as to regulate the temperature of the fluid medium flowing to said heat exchanger so as to maintain the air in said space at the desired temperature, humidity responsive means for adjusting said valve means to cause medium at a minimum temperature to flow to said heat exchanger, and means causing said flow to take place alternately at relatively low and high rates.

WILLIAM L. McGRATH.
